UNITED STATES PATENT OFFICE.

J. CARROLL HOUSE, OF LOWVILLE, NEW YORK.

BURIAL-CASE.

SPECIFICATION forming part of Letters Patent No. 320,254, dated June 16, 1885.

Application filed July 19, 1884. (Model.)

To all whom it may concern:

Be it known that I, J. CARROLL HOUSE, a citizen of the United States, residing at Lowville, in the county of Lewis and State of New York, have invented a new and useful Burial-Case for the Preservation of the Remains of the Dead, of which the following is a specification, reference being had to the accompanying drawings, in which—

10 Figure 1 is a perspective view of the entire case with sections of the superimposed sheets of asbestos removed to show the skeleton framework within. Fig. 2 is a vertical cross-section showing the method of construction and 15 the manner in which the material in its several layers is built up and the position of the skeleton support-frame embedded in the body of the same.

Similar letters indicate similar parts.

20 In the construction of my improved burial-case two light "forms" of well-seasoned material are first made, the contour of whose exterior represents the design and shape which the interior of the completed case is desired to have, 25 the one for the upper and the other for the lower section. These forms are attached by their broadest faces to some base-boards which extend a couple of inches beyond their margins at the sides and ends. The exposed surfaces of the forms and base-boards are saturated with some good hard-drying wood filling and smoothly polished. Each section of the intended case is then made as follows: A sheet 30 of asbestos felt, A. A, from one-sixteenth to one-eighth of an inch in thickness, is first neatly fitted to the form, being allowed to extend out from the same about two inches upon the surface of the base-board all around, and is then lightly secured by tacks driven so as to 35 be easily withdrawn. The corners of this felt covering are now to be covered with stout canvas stays firmly glued or cemented on, and the entire surface is to be saturated with a 40 solution of asphaltum in some quick-drying solvent, such as spirits of turpentine or naphtha, and allowed to dry. A skeleton frame of heavy 45 galvanized hoop-iron, the width and thickness to be governed by the size of the case, and the individual strips thereof running lengthwise and crosswise at right angles, and soldered or riveted at their points of intersection, is

now fitted over the felt-covered form, the extremities of the strips being furnished with holes and bent out horizontally, as at B B, from an inch to an inch and a half. The 55 frames of the upper and lower sections, respectively, are so constructed that the horizontal ends of the strips shall coincide when placed in their position in the completed case.

The skeleton frame having been properly 60 adjusted to the form, it is removed, and the asbestos receives a thick coat of melted asphaltum, and while this is hot the frame is replaced *in situ* and well pressed into the asphaltum. Pieces of asbestos felt are then 65 to be fitted between the strips of the frame, of a thickness corresponding to that of the strips of the frame, the surfaces of which are to be saturated with dissolved asphaltum, and they are to be firmly pressed down upon the asphaltum-covered base felt, which is all allowed 70 to dry thoroughly. A third sheet (entire) is now to be fitted over the entire form and then removed, that the two approximating surfaces may each receive a good coat of dissolved asphaltum, when the adjusted felt is to be placed 75 in position on the form and well rubbed and pressed down to a firm contact with the same, and allowed to dry. Another sheet of the asbestos felt is again to be adjusted to the above, 80 and then removed, and a very thin mixture of calcined gypsum or plaster-of-paris in water is quickly brushed over the asbestos-covered form, while at the same time the adjusted sheet is being passed through a suitable vessel 85 containing a similar mixture, and when thoroughly saturated is quickly laid in place upon the form and snugly pressed to place, and brought to the shape of the basal plates beneath, and there firmly retained until the 90 gypsum shall have time to crystallize or set and the surplus moisture to evaporate. If desirable, the plaster-of-paris may be mixed 95 with a solution of silicate of soda or potash, or of gelatine, to give it greater strength and firmness. These layers of asbestos and asphaltum or plaster-of-paris may be increased as the size of the case may demand thickness or strength, each layer having the corners strengthened by stout canvas, as in the case 100 of the first covering. The sheets of asbestos may be first rendered water-proof before ar-

ranging them over the form, if so desired, by treating them with any solution or preparation which will accomplish the same. When the requisite number of superimposed layers 5 have been added and the whole mass is thoroughly dried, the shell so constructed is lifted from the form and the edge of what now constitutes a flange around each half or section is neatly trimmed to a proper width, say one 10 and one-half inch on the face. It will now be found that when these two sections or shells are brought face to face they constitute a substantial coffin or burial-case, the interior of which can be lined and suitably ornamented 15 by attaching the requisite material to the inner layer of asbestos by glue. The outside may be saturated with some good body-stuffing or painter's grounds and thoroughly rubbed down and then finished in any desirable 20 colors or wood imitation, or it may be covered with cloth by attaching the same with glue, as is the practice in the external ornamentation of the ordinary wooden caskets. The ends of the galvanized-iron skeleton frame 25 as they lay embedded in the flanges opposite each other are to be punctured, and through these openings, when the shells are in place, binding-screws or bolts and nuts with washers are passed to hold the sections together. The 30 ends of these screws when exposed may be made of any ornamental design and silver-plated, as desired. When it is desired to make the case air and gas tight, a soft lute of asphaltum, tallow, beeswax, and turpentine or 35 naphtha is to be smeared upon both flange-faces after the body to be interred is in place and before the sections are finally brought together and properly secured by the screws which bring the two faces together. In some 40 cases it may be desirable to further strengthen these flanges by a strip of wood neatly fitted around the outside and bedded into the asphaltum coat on the last layer of asbestos, and the binding-screws are to pass through

this stay. The handles by which the case is 45 to be carried are to be secured to the same by the screws which are used to bind the sections together, thus giving the strain upon the iron frame-work and not the asbestos pile of the case. 50

A modification in the detail of construction is so forming the sections of the shell that the upper portion shall set down over the upper edge of the lower like the parts of a paper box, in which case the screws that unite the 55 two sections pass through the two horizontally along the line of their overlapping, and thus bind the two firmly together.

The principle of construction embodied in the above described case may be used when 60 wood or paper pulp or woolen felt material is substituted for the asbestos, but a case so constructed cannot be said to be imperishable in the proper sense of the term.

A heavy plate-glass can be bedded on the 65 proper layers in the upper part of the top section when it is desired to have the case arranged to view the remains inclosed, suitable openings being left in the superimposed layers for said purpose. 70

I claim—

A burial-case constructed of layers of asbestos, superimposed over a suitable form, said layers being cemented each to the other by a stratum of asphaltum or its equivalent, 75 and one or more of the respective layers saturated with a solution of asphaltum or its equivalent, to render it water-proof, the whole strengthened and supported by transverse strips of metal soldered or united at their 80 points of intersection and retained in place between layers of the constituted case, substantially as and for the purpose specified.

J. CARROLL HOUSE.
